CUTICLE REMOVER

Frederick Grodka, Berlin, Germany, assignor to
Progress Corporation, New York, N. Y., a cor-
poration of New Jersey

Application May 11, 1937, Serial No. 141,944
In Germany May 11, 1936

6 Claims. (Cl. 132—73)

This invention relates to manicuring instruments and more particularly to an instrument for removing cuticle from around the fingernails of the human hand.

5 The invention contemplates the provision of an instrument of substantially the size and shape of a fountain pen which is adapted to store a quantity of liquid for treating the cuticle, said liquid being adapted to be fed to the cuticle tool or stick positioned at the end of said instrument.

The contemplated features of the invention reside in the provision of improved means for feeding the liquid preparation contained in the instrument to the tip of the cuticle stick; in the 15 structural features of the valving means; and in the manner in which the parts of the instrument are arranged to afford easy and positive manipulation thereof.

The above generally stated features and many 20 others which will become apparent as this specification progresses, are incorporated in the several embodiments of the invention as illustrated, in their present contemplated forms, in the accompanying drawings on which the following description is based.

In the drawings:—

Fig. 1 is a longitudinal sectional view of a cuticle removing instrument in one of the forms herein contemplated.

30 Fig. 2 is a similar view, broken away, of the instrument viewed at right angles to the showing of Fig. 1, the valving means being in a closed position.

Fig. 3 is a view similar to Fig. 2 with the valving means in open position.

Fig. 4 is a part elevational, part sectional view of another form of cuticle removing instrument.

Fig. 5 is a longitudinal sectional view, partly broken, of the instrument shown in Fig. 4 and 40 viewed at right angles thereto.

Figs. 6, 7, and 8 are cross-sectional views taken respectively on the lines 6—6, 7—7, and 8—8 of Fig. 4.

45 Fig. 9 is a partly broken longitudinal sectional view of a device embodying the invention in still another form.

In greater detail, and with particular reference to Figs. 1 to 4, inclusive, the barrel or housing 10 is provided with a removable cap 11 and a separable end portion 12. As shown, said end portion is provided with a flexible container or sac 13 for a liquid preparation 14 which is adapted to be fed to the hollow cuticle tool or stick 15 50 rotatably mounted in the bore 16 of said end por-

tion. The sac 13 is preferably made of rubber or rubber composition.

The cuticle stick 15 is preferably formed at its end 17 in the manner of an orange stick and is adapted to be used to press against and treat the 5 cuticle around the fingernails.

A channel 18 is formed in said stick for the passage of liquid from the flexible sac 13, said liquid passing through a hollow tube 19 fixedly held by the pin 20 within an extension of the bore 16 10 to a valving arrangement 21 positioned between the hollow 19a in the tube 19 and the channel 18.

The valving means 21 includes a cut or notch 22 formed in the stick 15, a recess 23 in the end portion 12 adapted to register with said notch 15 and in communication at 24 with the mentioned hollow 19a of the tube 19. In order to reduce the amount of liquid adapted to be held in the hollow 19a, the cuticle stick 15 is formed with an extension 15a smaller in diameter than the stick 20 so that a thin annular chamber is provided for the liquid between said extension and the walls of the tube 19.

Thus it can be seen that when the notch 22 is in register with the recess 23, as shown in Fig. 3, 25 liquid may pass from the sac 13, to the chamber 19a to the recess 23 through channel 24, notch 22, and thence through the passage 18 to the tip of the cuticle stick. When said notch and recess are out of register, as shown in Fig. 2, the 30 liquid is trapped in said recess and hence may not pass to the tip of the stick 15.

In order to limit the rotational positions of the stick, the extension 15a is preferably provided with a pin such as 25 engaged in a slot 26 in the 35 sleeve 19. When the pin 25 is positioned against one end of said slot, registration between the notch 22 and recess 23, is had; when positioned against the other end of said slot, the mentioned notch and recess are out of register. For the 40 guidance of the user, visual indicating means on the end portion 12 and adjacent parts of the stick, may be used.

Liquid may be fed in predetermined quantities to the tip 17 by compressing the sac 13 as by 45 means of the button 27. Pressing said button will flex the spring 28, which in turn, will move the plate 29 against the sac.

Compression of the sac 13 may also be had by depressing the top plunger 30 which is available 50 upon removal of the cap 11. This plunger 30 is only used for filling or emptying the sac 13 and is frictionally held in a bore 31 in the barrel 10, being slotted at 32 to receive the upper end of the spring 28.

While the instrument above described represents a considerable improvement over prior structures, a further advantage and development may be obtained in the provision of means hereinafter described to displace the necessity of grasping the stick in order to rotate it for the different valving positions. The form of the invention shown in Figs. 4 to 8, inclusive, is designed to bring about this advantage.

10 In this form of the invention, the tool or stick 15 is arranged to be rotated by means of a ring or band 35 mounted on the housing or barrel 10, the ring 35 carrying studs 36 passing through slots 37 in the barrel, and being connected to 15 upright arms 38 which are connected near their tops as by a circular portion 39 and at their bottom ends by a ring 40 having a substantially rectangular-shaped opening 41.

The mentioned rectangular opening is adapted 20 to receive a rectangular extension 42 above the flanged portion 43 of the stick 15. The ring 40 is adapted to seat against said flanged portion and to be held thereagainst by means such as the nut 44.

25 In order to maintain the flanged portion 43 against the seat 45 in the end portion 12, said end portion is fitted with a plug 46 fixedly held as by the pin 47, said plug being seated on the nut 44. Thus, the stick 15 is held against end 30 wise movement while being adapted to be rotated by manipulation of the band 35 guided by the slots 37 as shown in Fig. 6. The ends of these slots determine the rotational position of the stick 15 in the manner described for the form shown 35 in Fig. 1.

Liquid from the sac 13 may pass through a central bore 48 in the plug 46, to a similar bore 49 in the upper end of the stick 15, into a small 40 passage 50 opening at the bottom of the flanged portion 43 of the stick. In one rotational position of the stick, the seat 45 seals liquid from passing to the stick passage 18. In the other position, the passage 18 is in communication with the recess 23 so that liquid may pass therethrough 45 to the notch 22 which is in communication with said passage 18.

The button 27 which is used to compress the sac to feed liquid is arranged to pass through a slot 51 in the band 35, so that rotation of said 50 band may not affect the position of said button.

In the form of the invention shown in Fig. 9, in addition to the valving means previously described, the instrument is provided with a ball valve 55 positioned between the liquid containing sac 13 and the mentioned previously described 55 valving means. In this manner there is provided an auxiliary chamber 56 from which fluid is valved to the stick tip 17.

In this structure, the band or ring 35 is arranged to lineally reciprocate within the limits of space 37 to operate the ball valve and also to 60 rotate to operate the valving means 21. The arms 38 are arranged at their bottom ends to support the ball 55 against its seat under the urgency of 65 the spring means 57. Guide means 58 for the arms 38 are provided to permit vertical movement of said arms and said engagement between the arms 38 and the guide means 58 serve to transmit rotational movement of the band 35 to 70 the stick 15, since said guide means are fixed with said stick 15.

To prevent leakage of liquid from the auxiliary chamber 56 upward into the barrel 10, a sealing washer 59 is secured to the plug 46, said washer 75 being adapted to rotate with the arms 38 which

pass therethrough. It is understood that more than one washer may be employed to effect the sealing condition if warranted.

In the "on" position as shown particularly in Fig. 3, it will be observed that when the button 27 is not depressed no liquid will flow to the stick 15. This affords a condition to utilize the stick 15 as a dry instrument to massage the moistened cuticle, although it is preferable to shut off the flow of liquid to the stick by means of rotating 10 the stick to a position, as for instance, that shown in Fig. 2, 4 or 9.

A cover or cap 11a is preferably provided for the working tool end of the device.

From the foregoing, it is apparent that a desirable and useful instrument has been provided in several forms of embodiment.

While the preceding description is quite detailed, it does not exhaust the possible manners of practising the invention as claimed. Therefore, the prior art rather than the instant disclosure shown forms the basis of interpretation of the scope of the following claims.

Having thus described my invention what I claim as new and desire to secure by Letters Pat- 25 ent is:-

1. A cuticle remover comprising a housing, a flexible container for liquid within said housing, a rotatable working tool having a substantially rigid tip constructed for massaging the cuticle, 30 said tool having a passageway substantially therethrough and therein, positive means for limiting the rotation of said tool to selectively adjust said tool to its feeding and inoperative positions, communicable means between said container and 35 said passageway, said communicable means including hollows in said housing and said tool in positions for registry upon relative rotation of the housing and tool to its feeding position, and means for actuating said container to produce an 40 initial flow of liquid to said hollow in said housing, said communicable means and said actuating means relatively cooperating with each other to produce a regulated drop discharge through said 45 passageway.

2. A cuticle remover comprising a housing having a liquid receptacle therein, a rotatable working tool having a substantially rigid tip constructed for massaging the cuticle, said tool having a passageway substantially therethrough and 50 therein, means for limiting the rotation of said tool to selectively adjust said tool to its feeding and inoperative positions, communicable means between said receptacle and said passageway, said communicable means including 55 recesses in said housing and said tool in positions for registry upon relative rotation of the housing and tool to its feeding position, and means for producing an initial flow of liquid to said recess in said housing, said communicable means and 60 said producing means relatively cooperating with each other to provide a regulated drop discharge through said passageway.

3. A cuticle remover comprising a housing having a liquid receptacle therein, a working tool 65 having a passageway substantially therethrough and having a notch communicating with said passageway, said tool having a tip formed for massaging the cuticle, said housing having a recess in position for communication between said receptacle and said notch upon relative rotation of the tool and housing to an operative position, and means to cause liquid to flow from the receptacle to said recess, notch and passageway, respectively.

4. A cuticle remover comprising a housing having a liquid receptacle therein, a massaging tool having a passageway substantially therethrough and having a notch provided with a lower face within which the end of the passageway is disposed, said housing having a recess in position for communication with the notch upon rotation of the tool to an operative position relative to the housing, said recess having communication with the liquid receptacle, and means for causing liquid to flow from the receptacle to said recess, notch, and passageway.
5. A cuticle remover comprising a housing having a liquid receptacle therein, a working tool having a passageway substantially therethrough and having a notch communicating with said passageway, said tool having a tip formed for massaging the cuticle, said housing having a recess in position for communication between said receptacle and said notch upon relative rotation of the tool and housing to an operative posi-

tion, means to cause liquid to flow from the receptacle to said recess, notch and passageway, respectively, and means for rotating said working tool to operative and inoperative positions.

6. A cuticle remover comprising a housing having a liquid receptacle therein, a working tool having a passageway substantially therethrough and having a notch communicating with said passageway, said tool having a tip formed for massaging the cuticle, said housing having a recess in position for communication between said receptacle and said notch upon relative rotation of the tool and housing to an operative position, means to cause liquid to flow from the receptacle to said recess, notch and passageway, respectively, and means for rotating said working tool to operative and inoperative positions, the last-mentioned means extending into the housing and being operable from externally thereof.

20
